UNITED STATES PATENT OFFICE

2,127,554

PRODUCTION OF TEXTILE THREADS AND FABRICS

Henry Dreyfus, London, England

No Drawing. Application May 22, 1936, Serial No. 81,266. In Great Britain May 31, 1935

10 Claims. (Cl. 117—2)

This invention relates to the manufacture of crêpe threads consisting of or containing filaments of regenerated cellulose.

It has been found that crêpe threads consisting of or containing filaments of regenerated cellulose may very advantageously be produced by crêpe twisting a thread of regenerated cellulose filaments and subjecting the thread, during the insertion of crêpe twist, to the action of steam 5 in a substantially closed chamber, or to the action of hot water, so that at least the last part 10 of the crêpe twist is inserted while the thread is under the influence of the steam or hot water.

In accordance with the present invention, therefore, in the production of highly twisted crêpe threads of regenerated cellulose, e. g. cellulose regenerated from viscose or cuprammonium solutions, the threads are, during the insertion of crêpe twist, subjected to the action of steam in 15 a substantially closed chamber, or to the action of hot water, so that at least the last part of the crêpe twist is inserted while the thread is under the influence of the steam or hot water. When using steam it is of great advantage to have moisture present. Thus the thread may be passed 20 through a substantially closed chamber maintained full of steam under such conditions that moisture is present, so that at least a portion of that part of the track of the running thread in 25 which twisting actually takes place is within the steam chamber. Twist is thus inserted while the thread is under the influence of a hot medium 30 which is substantially entirely aqueous.

By the new process it is possible to produce crêpe threads of regenerated cellulose filaments, said threads being very much stronger than those obtainable by crêpe twisting a thread of regenerated cellulose filaments without the aid of the steam or hot water. Moreover, the new threads 35 have for a given degree of twist superior crêping power, and with their aid crêpe effects may be obtained which are finer and more regular than those obtainable with regenerated cellulose threads which have been crêpe twisted in the 40 ordinary manner.

The threads may consist of substantially continuous filaments or they may consist of discontinuous filaments, the length of which may vary within wide limits. For example the threads may 45 be those spun from a mass of discontinuous filaments or those prepared in the manner described in British Patents Nos. 424,683 and 424,830.

If desired the filaments of the threads may contain water-insoluble compounds, whether 50 compounds of pigment-like character in such

form as materially to modify the lustre of the filaments (e. g. barium sulphate or titanium dioxide), or loading metal compounds, for example tin compounds.

In carrying out the new process twisting is very 5 advantageously effected on a device of the kind in which the thread is drawn off over the end of a rotating package through a guide fixed substantially in line with the axis of rotation of the package and is thereafter wound on a bobbin 10 or the like, the thread being passed through the steam chamber or the hot water on its way from the guide to the bobbin. In this way the yarn is subjected to the action of the steam or hot water during the actual insertion of twist. 15

On the other hand, any other suitable crêpe twisting device may be employed. For example a ring twister may be used for the crêpe twisting of thread consisting of discontinuous filaments. 20

The twisting spindle, the guide fixed in line with the axis of the spindle, and the steaming device or the hot water treatment device, should be so arranged that the twist resulting from the rotation of the package is at least partly inserted 25 while the thread is under the influence of the steam or hot water. For example when twisting the thread by the rotation of a package from which the thread is being drawn off, if the freedom of the thread to rotate within the balloon 30 guide or other guide preceding or forming part of the treatment device is unduly restricted, e. g. by causing the thread to change direction materially at the guides, the insertion of twist while the thread is under the influence of the steam or 35 hot water may be restricted to an undesirable extent or substantially prevented and the resulting crêpe threads may not have the valuable properties which may otherwise be secured. Thus when using a twisting device of the kind in which 40 thread is drawn off over the end of a rotating package, it is advantageous to arrange that the path of the thread after leaving the balloon guide and through the treatment device, is substantially in line with the axis of the spindle. 45

In the case of a ring twister where twisting is effected by the rotation of a package on to which the thread is being wound, the thread passing through the steam chamber or the hot water on 50 its way from the let-off device to the twisting spindle, a change of direction at the point at which the thread leaves the steam chamber or the hot water is of less importance as the thread remains under the influence of the steam or hot 55

water for a short time after leaving the steam chamber or hot water as the case may be.

The phrase "twist is inserted while the thread is under the influence of the steam or hot water" 5 means that that portion of the run of the thread in which twist is being inserted is either in the steam or hot water or still under the influence of the steam or hot water.

If desired, the above-mentioned twisting devices, in which the thread is drawn off over the 10 end of a rotating package, may be provided with a device which restricts the ballooning of the thread or the tendency of twist to run back to the package. As examples of such devices may be 15 mentioned flyers and the floating ring device described in U. S. Patent No. 1,784,581. The latter device is of particular value when the thread to be twisted is of very low twist, for example less than about 1 turn per inch.

20 When employing steam the new process may be carried out using a vertical twisting spindle of the type in which thread is drawn off upwardly over the end of a rotating package through a guide substantially in line with the axis of the 25 spindle, provided with a small chamber situated vertically above the spindle. The chamber is provided with small holes, top and bottom, to permit passage of the thread, and also with a steam inlet. If desired, a single steam chamber 30 may be arranged to serve a number of spindles, being provided with inlet and outlet holes for the thread of each spindle. Such an apparatus may conveniently consist of a horizontal pipe mounted over a row of spindles and provided with 35 eyes of porcelain, stainless steel, or other suitable material at appropriate points on top and bottom for the entrance and exit of the threads. The diameter of the pipe is sufficient to afford the thread the requisite length of travel in the 40 steam. Steam may be admitted to the pipe at one point or at more than one point as may be necessary according to the length of the pipe, to secure sufficiently uniform conditions of steaming as between the threads from the different 45 spindles.

If desired the pipe may be of less diameter than affords the thread the requisite length of travel and be fitted with upwardly projecting vertical tubes communicating with the inside of the 50 pipe at their lower ends, closed at their upper ends except for eyes for the passage of the thread, and of such length as to afford, together with the diameter of the pipe, the required length of path in the steam for the thread. The threads 55 enter by eyes in the lower side of the horizontal pipe and leave by the eyes in the upper ends of the vertical tubes.

At the point at which the thread from the twisting spindle enters the steam chamber, it 60 is advantageous to arrange a free escape of steam on to the thread as it is drawn off from the spindle. A shield, for example in the form of a funnel, may, if desired, be fitted around the thread approaching the steam chamber in order 65 to maintain an atmosphere of steam around the thread.

The presence of the desired moisture may be 70 assured by arranging for the condensation of steam. Dry steam may be passed through water so as to saturate the steam and the requisite moisture produced by cooling in the steam chamber. The above mentioned form of steam chamber comprising a horizontal pipe with upwardly 75 projecting tubes to afford the requisite length of path in the steam for the threads is advantage-

ous when condensation of steam is desired. Another method of ensuring the presence of moisture is to wet the thread with water; for example the bobbins of thread may be wetted before the twisting operation or better, water may be applied to the thread, by means of a wick or other device, after the thread leaves the spindle and prior to its entering the steaming device. The water may contain a substance which facilitates wetting of the thread by water.

Good results may be obtained by using steam at above 90° C. Steam temperatures in the neighbourhood of 100° C., for example 95 to 100° or 98 to 100° C. are advantageous. Steam at about atmospheric pressure, e. g. slightly above atmospheric pressure, is conveniently employed. However, if desired steam may be effected with steam at any desired superatmospheric pressure, e. g. steam at 10 to 25 lbs. per square inch.

The path of the thread through the steam 20 chamber may be comparatively short, for example 1 to 3 inches, though longer paths may be employed if desired, for example 3 to 6 inches.

Treatment of the thread with hot water during 25 twisting may be effected by drawing the thread off from a twisting spindle and passing it upwardly through a suitable receptacle containing hot water and having a small hole below the water level for the passage of the thread, the 30 thread then passing to a winding device. The hole may be, for example, about $\frac{1}{2}$ of an inch in diameter and may be provided with means adapted to lead away and prevent from reaching the twisting spindle, any water issuing from the hole. If desired, the hole may take the form of 35 a short tube of fine bore, fixed in the receptacle, whereby the flow of water from the receptacle at the point of entrance of the thread may be reduced. A similar arrangement may be used when crêpe twisting is effected as the thread is 40 wound on to a rotating package. In this case the thread may conveniently pass downwards through the water to the twisting spindle. Another method is to supply hot water to the thread. For example, the thread may be caused to pass in 45 contact with a horizontally disposed roller, preferably circumferentially grooved, arranged to rotate in a bath of hot water and so to carry water to the thread.

The duration of the treatment with hot water 50 may be relatively short, such as may be secured when the thread is travelling at a speed of 2-10 metres per minute and is in contact with hot water for 1-3 inches of its travel. Lengthier treatments may however be employed.

The temperature of the water may be 80-100° C., for instance 90-100° C. If desired, the hot water may be employed under pressure, for example 2-10 or 15 pounds or more per square inch. The use of pressure enables the water to be employed at higher temperatures than is possible under atmospheric pressure. By using pressure, therefore, the temperature of the water may be above 100° C. and up to the boiling point of water at the pressure employed. Water may be employed under pressure, however, when the temperature is below 100° C. The hot water may contain agents which facilitate the wetting of the threads.

The initial thread may already be twisted 70 to a small degree, for example up to 10 turns per inch, e. g. to 2-5 turns per inch or to such small degree as is commonly applied to artificial silk continuously with the spinning thereof.

In carrying out the new process the crêpe twist 75

may be applied in a single stage. If desired, however, the crêpe twist may be applied in two or more stages, the final stage of twisting being effected whilst steaming the thread in a substantially closed chamber or whilst treating the thread with hot water.

When the crêpe twist is applied in two or more stages the advantages of the process may be obtained when not only the final stage of the crêpe twisting but an earlier stage or stages of twisting are also effected while steaming the thread or treating it with hot water. In fact it is of great advantage to effect, while steaming the thread or treating it with hot water, any application of twist beyond the point at which twisting would result in weakening of the thread if the said twisting were effected without the steaming or hot water treatment.

The precise degree of twist beyond which it is advantageous to steam or treat with hot water during twisting depends upon the total denier of the thread and the number of its constituent filaments. Generally at least the last half or two thirds of the total crêpe twist should be applied whilst steaming the thread or treating it with hot water.

The degree of twist applied in accordance with the new process may be that commonly employed in the production of crêpe threads of filaments of regenerated cellulose. For example, twists of from 40 to 75 turns per inch may be employed, according to the denier and number of filaments in the thread. Higher twists may, however, be employed, and a feature of the new process is that it enables very high degrees of twist to be applied without such a great weakening of the thread as is commonly experienced when high degrees of twist are applied without the steam or hot water treatment.

If the crêpe twist is applied in two or more stages the twist may be divided between the twisting stages in various proportions. Twist applied in the absence of the steam or hot water treatment should not be of such degree as to damage the thread. To this end, as indicated previously, twisting without the steam or hot water treatment should not be effected where the twist applied is sufficient to result in substantial weakening of the thread.

A particularly convenient method of working is to apply about one sixth to one quarter or one half of the total crêpe twist without the steam or hot water treatment, say up to 10 or 15-25 or even in some cases up to 30 turns per inch, and then to complete the crêpe twist while steaming the thread or treating it with hot water.

The regenerated cellulose filaments of the threads readily undergo stretching when the threads are twisted while steaming or treating with hot water. The amount of stretch may be measured by comparing the original thread denier with the final thread denier (after untwisting). The denier of the resultant thread is, in general, owing to imparted stretch, less than if the steam or hot water treatment is omitted. The stretch imparted to the filaments of the threads during the twisting operation may for example be of the order of 5 to 15 or 20 per cent. of their original length.

The invention is applicable to the production of crêpe threads consisting of, or containing, regenerated cellulose filaments of various kinds. As examples of such filaments mention may be made of those produced from viscose or from cuprammonium cellulose solutions. Again, the

filaments may be those obtainable by substantially completely saponifying filaments of cellulose acetate, cellulose nitrate, or other organic or inorganic ester of cellulose. If desired, the crêpe threads may be made with filaments of regenerated cellulose such as have been stretched, preferably those stretched while in a softened state. Saponified cellulose ester filaments, if desired, may be those obtainable by substantially completely saponifying cellulose ester filaments which have been stretched, for example while in a softened state, as described for instance in U. S. Patent No. 1,709,470 and British Patent Nos. 323,790, 370,430 and 371,461, or have been stretched in steam or hot water as described in British Patent Nos. 438,584 and 438,586.

The invention particularly contemplates the production of crêpe threads consisting wholly of regenerated cellulose filaments, whether wholly of filaments of regenerated cellulose of one kind or in part of filaments of regenerated cellulose of one kind and in part of filaments of regenerated cellulose of another kind. If desired, however, the threads may be composed in part of regenerated cellulose filaments, and in part of filaments of another material, for example, natural silk, wool or cotton. As in the case of regenerated cellulose filaments, such other filaments may be substantially continuous filaments and/or discontinuous filaments.

While the new process enables production of threads which yield satisfactory crêpe effects without a special treatment, other than the twisting and steaming or hot water treatment characteristic of the process, other devices and treatments may, if desired, be employed further to improve the properties of the crêpe threads and/or fabrics produced therefrom. For example, the twist may be irregular in character as described in U. S. Patent No. 2,061,614. Further, the crêpe threads may be sized at any suitable stage of their manufacture, for example prior to the application of twist, or at least any substantial proportion of the twist. In this connection, particular mention may be made of sizing materials selected in accordance with the considerations laid down in U. S. Patent No. 2,007,182. For example a casein, egg-albumen or other size which is not very readily removed by aqueous treatments may be employed. Sizing may also be effected with the aid of drying oils, for example boiled or blown linseed oil.

The highly twisted crêpe threads may be incorporated in the fabrics in various ways, for example the weft alone may be wholly or partially composed of such threads or the warp may also contain them. Valuable fabrics may be produced by employing warp threads of relatively low twist and in the weft both crêpe threads having a left-hand twist and crêpe threads having a right-hand twist, pairs of threads of left-hand twist alternating with pairs of threads of right-hand twist.

Fabrics containing highly twisted crêpe threads prepared in accordance with the invention may subsequently be given a hot aqueous treatment, for example in the manner commonly adopted in connection with fabrics comprising highly twisted yarns of natural silk. Such treatment may be, for instance, treatment in a hot aqueous soap solution at a temperature of 75-85° C. or at higher temperatures, e. g. at the boil.

Having described my invention what I desire to secure by Letters Patent is:—

1. Process for the production of a highly twisted

crêpe thread, which comprises crêpe twisting a thread containing regenerated cellulose filaments and during the insertion of at least the last part of the crêpe twist passing the thread through a substantially closed chamber maintained full of steam so that twist is inserted while the thread is under the influence of the steam.

2. Process for the production of a highly twisted crêpe thread, which comprises crêpe twisting a thread of regenerated cellulose filaments and during the insertion of at least the last part of the crêpe twist passing the thread through a substantially closed chamber maintained full of steam under conditions such that moisture is present, so that twist is inserted while the thread is under the influence of the steam.

3. Process for the production of a highly twisted crêpe thread, which comprises crêpe twisting a thread of regenerated cellulose filaments and during the insertion of at least the last part of the crêpe twist passing the thread through a substantially closed chamber maintained full of steam at above 90° C., under conditions such that moisture is present, so that twist is inserted while the thread is under the influence of the steam.

4. Process for the production of a highly twisted crêpe thread, which comprises crêpe twisting a thread of regenerated cellulose filaments in a single stage and during the insertion of the crêpe twist passing the thread through a substantially closed chamber maintained full of steam at above 90° C., under conditions such that moisture is present, so that twist is inserted while the thread is under the influence of the steam.

5. Process for the production of a highly twisted crêpe thread, which comprises crêpe twisting a thread of regenerated cellulose filaments in at least two stages and during the final stage of twisting passing the thread through a substantially closed chamber maintained full of steam under conditions such that moisture is present, so that twist is inserted while the thread is under the influence of the steam.

6. Process for the production of a highly twisted crêpe thread, which comprises crêpe twisting a thread of regenerated cellulose filaments and during the insertion of at least the last part of the crêpe twist passing the thread through a substantially closed chamber maintained full of steam under conditions such that moisture is present, so that twist is inserted while the thread is under the influence of the steam.

present, so that twist is inserted while the thread is under the influence of the steam, at least the last part of the twisting being effected by the rotation of a package on which the thread is being wound.

7. Process for the production of a highly twisted crêpe thread, which comprises crêpe twisting a thread of regenerated cellulose filaments and during the insertion of at least the last part of the twist passing the thread through a substantially closed chamber maintained full of steam under conditions such that moisture is present so that twist is inserted as the thread passes through the steaming chamber, at least the last part of the twist being effected by the rotation of a package from which the thread is being drawn.

8. Process for the production of a highly twisted crêpe thread, which comprises crêpe twisting a thread of regenerated cellulose filaments prepared by saponifying cellulose ester filaments, and during the insertion of at least the last part of the twist passing the thread through a substantially closed chamber maintained full of steam under conditions such that moisture is present, so that twist is inserted while the thread is under the influence of the steam.

9. Process for the production of a highly twisted crêpe thread, which comprises crêpe twisting a thread of regenerated cellulose filaments prepared by saponifying cellulose ester filaments which have been stretched, and during the insertion of at least the last part of the twist passing the thread through a substantially closed chamber maintained full of steam under conditions such that moisture is present, so that twist is inserted while the thread is under the influence of the steam.

10. Process for the production of a highly twisted crêpe thread, which comprises crêpe twisting a thread of regenerated cellulose filaments and during at least the last part of the twisting passing the thread through hot water in a container having below the water level a small hole for the passage of the thread, so that twist is inserted as the thread passes through the hot water, at least the last part of the twisting being effected by the rotation of a package from which the thread is being drawn.

HENRY DREYFUS. 50
